KENNETH M. SIMPSON, OF NEW YORK, N. Y.

PROCESS OF CARBONIZING COAL

Application filed June 28, 1924. Serial No. 723,022.

My process broadly consists in imparting to a series of moving receptacles a carbonizing heat while passing through a heating zone, and in introducing to said receptacles 5 pulverized carbonaceous material while moving through a cooler zone, the heat absorbed by the material constituting the receptacles being sufficient during this later movement to vaporize out the volatiles from the com-10 minuted carbonaceous material and leave a substantially carbonized product.

The invention also comprehends utilizing a continuous conveyor consisting of interconnected receptacles adapted to pass 15 through a heating zone to receive their carbonizing heat after which material is introduced to said vessels while moving through a cooler zone, the heat absorbed by the material constituting the vessels, being, however, 20 sufficient to carbonize the introduced charge of finely comminuted material. It is therefore apparent that no direct heat is applied to the vessels while filled with carbonaceous materials and that the low temperature carbonization occurs solely by reason of the heat 25 contained in the vessels.

In the accompanying drawings I have shown the preferred embodiment of an apparatus capable of supporting this process, in 30 which Figure 1 represents a longitudinal sectional view of my apparatus; and,

Figure 2 a cross section of the same.

Referring now more particularly to the drawings wherein like reference characters 35 indicate corresponding parts, the numeral 1 designates a furnace structure which may be formed of any desired and conventional material and which is provided with an open interior 2 adapted to receive the interposed 40 hearth 3 constructed of brick or the like. The bottom 4 of the furnace is formed with flues 5, these flues being adapted to conduct heating gases from the combustion chamber 5' seated beneath this wall. Gases or the like 45 are burned in the combustion chamber by means of the burner 6 to supply the necessary heat for carrying out the process.

The furnace is provided with a top wall having a vapor outlet 7 leading therefrom, 50 which extends to any suitable receiver, con-

denser or the like. The waste gases from the flues 5 pass into the collecting flue 8 at the side of the furnace, then up through the stack flue 9, then out the stack 10.

Disposed within the interior 2 of the furnace 1 near each side of the hearth 3 I provide sprockets 7' and 8 around which an endless conveyor 9 passes, the conveyor 9 consisting of a series of metallic pans 10 carried by sprocket chains 11 extending around the sprockets 7' and 8. These pans 10 substantially abut one another and offer a continuous conveying surface. The sprockets 7' and 8 are driven by hand or any suitable power mechanism.

It will be apparent that the flues 5 heat the under side of the retort 2 so that the metallic pans 10 receive their maximum heat while travelling on the under side of the hearth 3 and adjacent the flues 5. The retort near its forward end is provided with an outlet opening 13 which is sealed to prevent the discharge of heat from the chamber 2 and through which opening carbonized particles, coal and the like are discharged 75 from the pans 10, as they move around the sprockets 7'.

Adjacent the main conveyor 9 I provide an auxiliary conveyor 14, the same consisting of a series of pans similar to the pans 10 connected together by chains travelling around the sprockets 15 and 16. The auxiliary conveyor 14 feeds to the main conveyor 9, if this is found to be desirable, or the main conveyor can be fed entirely independently of the auxiliary conveyor. To this end I provide a feed 16' for the auxiliary conveyor and a feed 17 for the main conveyor. Pulverized materials, such as powdered coal, mixtures of coal and oil, and the like fill the feed hopper 16' and 17 and regulated quantities of this material can be dropped into the pans carried by the conveyor chains from time to time during the operation of the apparatus. It will be observed that the pans 10 are constructed of cast iron or similar metal which will absorb and retain sufficient quantities of heat when passing over the flues 5 to cause a low temperature carbonization of the material later introduced to said heated pans when 100

travelling over the hearth 3. It may be necessary at times to construct the pans of unusual thickness in order that they will retain sufficient heat to cause the carbonization. It is 5 one of the salient objects of this invention to also provide an improved process for the low temperature carbonization of fuels which may be carried out in an apparatus of the character herein disclosed.

10 The process briefly consists in subjecting a plurality of pans, vessels or the like to a temperature while they contain no coal or other carbonaceous fuels, and after said pans have been highly heated and while moving through 15 a cooler zone I then introduce to the pans charges of finely pulverized carbonaceous materials. The temperature of the pans is sufficient after the introduction of such materials thereto to vaporize out the volatiles 20 contained in the fine coal particles leaving a substantially carbonized residue. In the process it is necessary that the pans possess a sufficient quantity of metal or other material which will absorb and retain the desired 25 amount of heat to effect the carbonization of the coal. I have found, however, that pans constructed of relatively thick cast iron material will very satisfactorily perform this process.

30 In carrying out the process in the apparatus herein described, I heat the retort to a temperature well in excess of 700° C., the temperature being sufficient, however, to heat the cast iron pans 10 to a temperature of at least 35 700° C.

In each pan I deposit pulverized coal in a layer of say one-half inch thickness, which coal may be deposited directly to the pans 10 through the main feed 17 or may be pre-heated before it enters the pans in the main 40 conveyor by first having travelled the length of the auxiliary conveyor 14 from where it is discharged into the pans of the main conveyor 9. In other words, the supplemental 45 feed may be used if desirable, but it need not be used if satisfactory conditions can be obtained by depositing the material from the feed 17 directly into the pans of the main conveyor. The pans travel very slowly 50 through the main conveyor, and in fact just as soon as each pan passes around the sprocket 8 it receives its fuel charge and it may require approximately fifteen minutes to move this charge to the outlet 13 at the opposite side 55 of the retort. The hearth 3 is maintained at a comparatively high temperature so as to prevent a sudden cooling of the pans when moving above said hearth. In fact, when the pans are at a temperature of say 700° C. 60 when they move around the sprocket 8 said pans may be of a temperature of approximately 500° C. when passing around the sprocket 7. It will be apparent that during this heat treatment volatiles are being driven 65 from the coal charge, and these volatiles pass

out through the vapor discharge pipe 7. The carbonized residue from each pan is automatically discharged into the opening 13 as the pans pass around the sprocket 7.

It will be clearly apparent that it is vital 70 in this process that the cast iron pans should be of sufficient size to absorb that amount of heat necessary to distill the volatiles from the coal charges and to convert the residue into coke. The coal will ordinarily have to be subjected to a temperature of not less than 75 500° C. to properly cause its distillation and in carrying out this process I therefore utilize pans of sufficient thickness to retain this temperature when the pans are travelling 80 over the hearth 3. By this process the maximum temperature is not applied directly to the pans while they contain the coal undergoing treatment, but the heat absorbed in the pans during their heat treatment while free 85 of coal is utilized for the low temperature distillation of the coal subsequently applied to the heated pans.

Having thus described my invention, what I claim is:—

1. A carbonizing process consisting in 90 passing a series of receptacles through a heating zone to be heated by the application of heating gases to contain sufficient heat to carbonize coal, in then moving such heated receptacles to a zone where coal is introduced thereto in such quantities that the coal is carbonized by the contained heat of the receptacles, in moving the receptacles with the coal charges through a distilling zone where 95 the volatiles of the coal are removed and a carbonized residue produced without raising the temperature of such receptacles, and in discharging such residue from the receptacles.

2. A process for carbonizing materials, 100 consisting in passing a series of heat storing receptacles through a heating zone, in storing in such receptacles sufficient heat to carbonize a charge of coal, in introducing 105 charges of coal to such receptacles after their heat treatment, and in moving such receptacles with their contained charges through a distilling zone where the temperature of the receptacles is not raised and where the 110 volatiles are removed and a carbonized residue produced by the stored heat of the receptacles, and in discharging such residue after 115 the distilling treatment.

3. A continuous carbonizing process, 120 comprising moving a series of heat storing receptacles through a heating zone, in heating such receptacles while passing through said zone to a temperature to store in such receptacles sufficient heat to carbonize fuel charges, in introducing to the heated receptacles fuel charges to travel therein through a distilling zone where the volatiles of such charges are removed and the carbonized residue produced by the stored heat of said receptacles, 125 130

in discharging the carbonized residue after such treatment, and in collecting vapors produced during the distilling operation.

4. A process for carbonizing coal, consisting in passing heat storing devices through a heating zone where said devices are heated to a temperature to store therein sufficient heat to carbonize comminuted coal charges, in moving said devices after their heat treatment through a distilling zone, and in which zone coal charges are applied to said devices and undergo volatilization during passage through the distilling zone without substantially raising the temperature of said devices and by reason of the contained heat thereof, and in discharging the carbonized residue after such treatment.

In testimony whereof I affix my signature.
KENNETH M. SIMPSON.
